UNITED STATES PATENT OFFICE.

DAYTON P. WOLFORD, OF TOLEDO, OHIO.

FLOOR-POLISHING IMPLEMENT.

Application filed July 10, 1922. Serial No. 573,942.

To all whom it may concern:

Be it known that I, DAYTON P. WOLFORD, a citizen of the United States, residing at Toledo, in the county of Lucas and State of 5 Ohio, have invented new and useful Improvements in Floor-Polishing Implements, of which the following is a specification.

My invention relates to a device particularly designed and adapted for polishing 10 floors. An object of the invention is to provide a floor surfacing or polishing implement having sufficient flexibility to readily conform to any irregularities of the floor surface over which it is moving, and which 15 at the same time is free from any tendency to double up while in use or when the forward end thereof strikes an obstruction.

A further object of the invention is to provide an efficient floor polishing device 20 which can be pushed over the floor with much greater ease than the usual heavy blocks that are used for this purpose, that will not break or mar furniture with which it may come in contact, and which can be 25 readily worked beneath articles of furniture or other objects which are spaced only a short distance from the floor, such as couches, bookcases, radiators, et cetera.

Other features of the invention will appear 30 hereinafter.

In the accompanying drawings, which will illustrate a device embodying the principles of my invention:

Figure 1 is a perspective view of the 35 device.

Figure 2 is a fragmentary section at the line 2—2 on Figure 1.

Figure 3 is a section at the line 3—3 40 on Figure 1, a portion of the device being broken away.

Figure 4 is a perspective view of the inner sack or casing.

Figure 5 is a perspective view of the device with the handle removed.

In its preferred form, the floor polisher 45 comprises an inner sack or receptacle 10 made of canvas or other strong and durable fabric. This receptacle is divided into a series of sections or individual compartments by seams 12 extending transversely of the receptacle. These compartments are filled with some heavy comminuted material to give weight combined with sufficient 50 flexibility so that the polisher will readily conform to irregularities in the floor sur-

face, and will also be sufficiently soft and yielding to prevent damage to the woodwork and articles of furniture which it may strike in ordinary use. For a filler I prefer to use small lead shot 13, although satisfactory 60 results may be obtained with various other materials.

The body of the implement, comprising the receptacle 10 with its filling 13, is contained in an outer casing 14 which is made 65 of canvas or like material. To the under side of the case 14 is attached a bottom piece 15 made of velour or other thick heavy fabric suitable for polishing floors. The bottom piece 15 underlies the entire casing 70 10 and may be attached thereto by means of a binder 16^a. If desired, the piece 15 may itself form the bottom of the casing. The rear end of the casing 14 is open to permit the insertion and removal of the container 75 10 which fits snugly therein.

The upper side of the casing 14 has an extension 16 and the sack 10 has a similar extension 17, said extension forming flaps for the attachment of a handle 18. The handle 80 may be provided with a clamp of standard construction comprising a clamping rod 19 having its ends fixed in the handle, and a co-operating clamping member 20 which is moved into clamping position by a thumb 85 screw 21.

In assembling the parts, the body (10, 13) is slipped into the casing 14, the flaps 16, 17 are inserted between the clamping members 19, 20, the clamp being then drawn up 90 close to said body, and the clamp tightened. The flaps are then tucked in between said body and the bottom piece 15. There is thus provided a flexible or hinge connection between the handle and body, permitting the 95 handle to swing about the axis of the rod 19 (Fig. 3) to any convenient angle during the operation.

The position at which the handle is attached, and the method of attaching it to 100 the body of the implement, in combination with the flexible type of body described, are of practical importance as they overcome or prevent any tendency of the body to buckle or double up when in use.

Although I have described the surfacing element 15 as a polishing material, it is to be understood that sand paper, garnet paper, emery cloth and various other abrasives and surfacing materials might be employed, 110

adapting the implement for various surfacing operations.

Modifications may be resorted to within the spirit and scope of my invention.

5. What I claim is:

1. A floor surfacing implement comprising, in combination, a body of finely divided heavy material, a container therefor made of flexible fabric and presenting a broad flat bottom surface yieldable under the weight of said material to conform to irregularities in the floor or surface being worked and to thereby distribute the weight over said surface, and means for pushing the implement 10 forward over a floor, comprising a rigid handle having a flexible connection with the body portion of the implement.
2. A floor polishing implement comprising, in combination, a filling of finely divided heavy material, a sack in which said material is packed, a facing for said sack of heavy fabric providing a broad, flat polishing surface, and means for pushing the implement over a floor.
3. A floor surfacing implement comprising a container, a filler of heavy material divided into particles with which the container is packed to form a flexible body, said body shaped to present a broad, flat bottom surface yieldable under the weight of said material to conform to irregularities in the floor or surface being worked and to thereby distribute the weight over said surface, the dimensions of said surface being greater than the vertical dimensions of the container, and means to push the implement over the surface of a floor.
4. A floor surfacing implement comprising a flexible container, a filler of units of permanent heavy material, said container being divided into a series of individual compartments by transverse seams and shaped to present a broad, flat bottom surface, each of said compartments containing a multiplicity of said units, said surface being flexible under the weight of the filler to conform to irregularities in the floor surface, means attached at one edge of the container for pushing it over the surface to be worked, and means cooperating with the container to prevent it from buckling or doubling up as it is pushed over the work surface.
5. A floor surfacing implement comprising an inner sack, an outer sack or casing, said inner sack being filled with a heavy solid material divided into small individual masses or particles to form a flexible body, and a rigid handle having a flexible connection with the body of the implement.
6. A floor surfacing implement comprising an inner sack, an outer sack or casing, said inner sack being filled with a heavy solid material divided into small individual

masses or particles, said inner sack being divided into a plurality of compartments each packed full of said material.

7. A floor surfacing implement comprising an inner sack, an outer sack or casing, said inner sack being filled with a heavy solid material divided into small individual masses or particles, said sacks each being provided with a flap at one end thereof, a handle, and a clamp on said handle to engage said flaps.

8. A floor surfacing implement comprising a flexible container, a filler therefor packed with a multiplicity of small units of heavy material forming a flexible body, said body shaped to present a broad, flat bottom surface yieldable under the weight of said material to conform to irregularities in the floor or surface being worked and to thereby distribute the weight over said surface, and a rigid handle having a flexible connection with the rear end of said body.

9. A floor surfacing implement comprising a container, a filler of small, substantially spherically units of permanent, heavy material, said container being divided by transverse seams into a series of individual compartments, said implement having a flexible work engaging surface yieldable under the weight of said material to distribute the weight over said surface.

10. A floor polishing implement comprising, in combination, an inner canvas sack packed with shot and divided into a series of compartments by transverse seams, said sack with its packing forming a broad, flat body, an outer canvas sack or casing closely fitting said inner sack, and a flat bottom of velour forming a polishing surface.

11. A floor polishing implement comprising, in combination, an inner canvas sack packed with shot and divided into a series of compartments by transverse seams, said sack with its packing forming a broad, flat body, an outer canvas sack or casing closely fitting said inner sack, a flat bottom of velour forming a polishing surface, said sacks provided at their rear ends with flaps, a handle, and a clamp on said handle removably attached to said body by means of said flaps.

12. A floor surfacing implement having a pliant surfacing member, a pliant weight member mounted on the surfacing member and attached thereto, the weight member substantially covering the surfacing member, and a stiff control member attached to the weight member for swinging movements relative thereto and operable to impart surfacing movements to the two members.

13. A floor polishing implement having a relatively shallow weight member of considerable surface covering area and easily pliant to conform to irregular surfaces, said

member having a removable pliant bottom facing for polishing purposes, and a handle hingedly attached to an edge portion of said member and operable to impart polishing movements thereto.

14. A floor surfacing implement having a bag-like member provided with a plurality of compartments arranged side by side, a comminuted weight material filling the bag compartments and a surface working member on the bottom side of the bag-like

member, the filled bag and the surface working member being pliant to accommodate themselves to irregular surfaces, and a handle hingedly attached to the bag-like member and operable to impart surface working movements thereto. 15

Signed at Toledo, in the county of Lucas and State of Ohio, this 7th day of July, 1922.

DAYTON P. WOLFORD.
